FLOODLIGHTING LUMINAIRE

Edmund L. Izzi, North Olmsted, Ohio, assignor to Westinghouse Electric Corporation, a corporation of Pennsylvania

Filed Oct. 15, 1965, Ser. No. 87,510

Term of patent 14 years

(Cl. D48—20)

FIG. 2.

FIG. 1.

FIG. 3.

FIG. 4.

FIG. 5.

FIG. 6.

FIG. 7.

FIGURE 1 is a front elevational view of a floodlighting luminaire showing my new design;

FIG. 2 is a side elevational view thereof;

FIG. 3 is a top plan view thereof;

FIG. 4 is a rear elevational view thereof;

FIG. 5 is a bottom view thereof;

FIG. 6 is a perspective view of my design; and

FIG. 7 is a view looking directly into the louvered grill.

The dominant features of my new design reside in the portions as shown in full line.

I claim:

The ornamental design for a floodlighting luminaire, substantially as shown and described.
